[57] CLAIM

The ornamental design for an on-premise enclosure for cable television components or the like, as shown and described.

DESCRIPTION

FIG. 1 is top, front, and left side perspective view of an on-premise enclosure for cable television components or the like showing our new design;

FIG. 2 is a front elevational view thereof;

FIG. 3 is a right side elevational view thereof;

FIG. 4 is a bottom view thereof;

FIG. 5 is a top view thereof;

FIG. 6 is a rear elevational view thereof;

FIG. 7 is a left side elevational view thereof;

FIG. 8 is a top, front, and left side perspective view thereof, with one of the doors shown in an open position; and

FIG. 9 is a top, front and left side perspective view thereof, with both of the doors shown in an open position.

The broken-line elements in FIGS. 8 and 9 are shown for illustrative purposes only and form no part of the claimed design.
